ELECTRIC PIANO

Harold B. Rhodes, 2443 Greenbriar St., Anaheim, Calif., assignor, by mesne assignments, of one-half to Fender-Rhodes, Inc., Fullerton, Calif., a corporation of California

Filed June 18, 1964, Ser. No. 80,469

Term of patent 14 years

(Cl. D56—9)

FIGURE 1 is a perspective view of an electric piano embodying my new design;

FIGURE 2 is a top plan view thereof;

FIGURE 3 is a front elevational view;

FIGURE 4 is a rear elevational view;

FIGURE 5 is a side elevational view looking from the left of FIGURE 3; and

FIGURE 6 is a side elevational view looking from the right of FIGURE 3.

The bottom of the electric piano is substantially plain.

I claim:

The ornamental design for an electric piano, substantially as shown and described.
